[57] **CLAIM**

I claim the ornamental design for handmixer, as shown and described.

DESCRIPTION

FIG. 1 is a top/front/right-side perspective view of a handmixer showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

The broken line showing of a portion of a power cord is for illustrative purposes only and forms no part of the claimed design.
